UNITED STATES PATENT OFFICE.

CHRISTEN CHRISTENSEN, OF BROOKLYN, NEW YORK.

IMPROVEMENT IN ROTARY ENGINES.

Specification forming part of Letters Patent No. 33,184, dated September 3, 1861.

To all whom it may concern:

Be it known that I, CHRISTEN CHRISTENSEN, of Brooklyn, in the county of Kings and State of New York, have invented a new and Improved Rotary Engine; and I do hereby declare that the following is a full, clear, and exact description of the same, reference being had to the accompanying drawings, forming part of this specification, in which—

Figure 1 represents an elevation of my invention looking in the direction of arrow 1, Fig. 2. Fig. 2 is a longitudinal vertical central section of the same. Fig. 3 is an end elevation of the same looking in the direction of arrow 2, Fig. 2. Fig. 4 is a transverse vertical section of the same, the line $\alpha\alpha'$, Fig. 2, indicating the plane of section.

Similar letters of reference in the several views indicate corresponding parts.

This invention consists, first, in the peculiar arrangement of two notched dogs running in and being guided by the grooved face of a rotary disk, in combination with a tooth secured in the face of said disk and with a series of levers, arms, and toothed segments, and with the rising and falling abutment in such a manner that by the action of the tooth on said notched dogs the abutment is raised and depressed by a positive motion in whatever direction the piston turns; second, in the arrangement of cam on the rotary shaft, in combination with a cut-off valve, in such a manner that the steam is cut off during the time the abutment is raised and an escape or loss of steam is prevented; third, in the employment of conical packing-rings, in combination with an inclined surface on the sides of the piston-wheel and with annular disks having conical projections on their inner surfaces, in such a manner that by tightening the screws which secure said annular disks to the cylinder the packing-rings are forced up tight simultaneously against the inclined surface of the piston-wheel and against the inner surface of the cylinder, and that the joints can always be kept perfectly tight without opening the cylinder simply by tightening said annular disks; fourth, in the arrangement of annular packing-pieces guided by hinged pins and forced into the corners of the box containing the abutment by means of suitable springs, as will be hereinafter more fully explained; fifth, in the peculiar con-

struction of the piston, which is forced against the inner surface of the cylinder by means of springs, and which is prevented from catching in the opening of the abutment by a cross-bar retained by cams during the time the piston passes said opening; sixth, in the arrangement of a pointer, in combination with a groove or mark on the central shaft of the piston, in such a manner that by its aid the correct position of the piston can be ascertained whenever it is desired, and, seventh, in the employment of conical metallic stuffing-boxes, in combination with the tapering ends of the central shaft, for the purpose of insuring a correct position of the piston.

The piston-wheel A, which runs in the interior of the stationary cylinder B, is firmly secured to the rotary central shaft C. The piston D, which projects from the piston-wheel A, runs air-tight on the inner surface of the cylinder and the steam passes into the annular space between the inner surface of the cylinder and the outer surface of the piston-wheel on one side of the abutment E and out on the other through the ports $a a'$, either one of which may be the steam or the exhaust port, according to the direction in which the engine runs. The abutment E is connected to bars b, which extend upward through stuffing-boxes c, and to which a rising and falling motion is imparted by arms $e e'$, that are connected to rock-shafts $f f'$. These rock-shafts have their bearings in arms $g g'$, and they are geared together by toothed segments $h h'$, so that they both oscillate up and down simultaneously in opposite directions. The toothed segments are raised or depressed by the action of a tooth i, which is secured to the circumference of a disk F, that is firmly attached to the central shaft C. Two grooves $j j$ in the circumference of this disk form the guides for the dogs G G', and notches $k k'$ in these dogs afford a hold to the tooth i as it revolves with the disk F. The ends of the dogs are slightly turned up or rounded, so that the tooth passes readily under them, and the edges of the notches are square on both sides, so that the tooth i in catching in one of said notches pulls or pushes the dog along in whatever direction the disk F may rotate. The dogs G G' are suspended from the short arms $l l'$ of bell-crank levers $l m l' m'$, that are fulcrated on stationary pivots $n n'$, projecting

from the head of the cylinder. The long arms $m m'$ of said bell-crank levers connect by rods $o o'$ with the toothed segments $h h'$. If the disk F is now rotated in the direction of the arrow marked upon it in Fig. 1, the tooth i will catch the inner edge of the notch k , thereby carrying the dog G along and raising, through the action of the bell-crank lever $l m$, rod o , and toothed segment h , the abutment E, and on arriving at the dog G' the tooth i catches at the outer edge of the notch k' and carries the dog G' out a sufficient distance to depress the abutment through the action of the bell-crank lever $l' m'$, rod o' , and toothed segment h' . If the engine turns in the opposite direction, the action of the tooth i on the dogs G G' will be precisely the same; but the dog G' will now come into action first and the dog G afterwards, and in both cases the abutment is raised and depressed by a positive motion. The abutment slides up and down in the box E' and the joints between its ends and the ends of said box are rendered tight by packing-pieces $a^2 b^2$. The rectangular packing-pieces a^2 are forced out against the ends of the box E' by springs c^2 , being guided by pins d^2 , and the conical packing-pieces b^2 are guided by the hinged pins e^2 and forced out into the corners of the box E' by means of springs f^2 . During the time the abutment is raised from the surface of the piston-wheel the steam is cut off by the action of a cam H, which is firmly secured to the central shaft C. On the opposite side of the disk F and which acts on the lower extremity of the stem p that connects with the cut-off valve I. The cam H is placed in such a position that it acts on the valve I just before the tooth i comes in contact with one of the dogs G G', and that the valve I is closed just before the abutment is lifted from the surface of the piston-wheel, and said cam is of such a shape that it acts either way and that the valve I is kept closed until the abutment is again depressed on the surface of the piston-wheel. By these means a loss of steam during the time the abutment is raised is most effectually prevented.

The joints between the piston-wheel A and the cylinder B are rendered tight by conical metallic packing-rings q , which are inserted into the open ends of the cylinder, so as to bear on inclined faces r on the sides of the piston-wheel, as clearly shown in Fig. 2. The packing-rings q are forced up against the inclined faces r of the piston-wheel by means of conical projections s , attached to annular disks J, that are secured by means of screws t to the ends of the cylinders. The shape of the packing-rings q is such that by tightening up the screws t they close up tight simultaneously against the inner surface of the cylinder and against the faces r of the piston-wheel, thus making a perfect and an adjustable joint between the piston-wheel and the cylinder. The most essential advantage of this packing, however, lies in the fact that it can be tightened from the outside

without opening the cylinder, it being hardly necessary to stop the engine.

The piston D is secured to the circumference of the piston-wheel A by means of solid plates u , which extend all the way across the surface of the piston-wheel. These plates form the guides for the packing-pieces $v w$, which are arranged somewhat similar to the packing-pieces $a^2 b^2$ of the abutment. The middle piece v is attached to guide-pins g^2 , which pass freely through the rim of the piston-wheel, being keyed to a cross-bar h , that is forced toward the center of the piston-wheel by means of a weak spring i^2 . Two (more or less) springs j^2 force the packing-piece v out toward the inner surface of the cylinder. The ends of the piece v are inclined to correspond to the inclined ends of the pieces w , so that a pressure exerted on these latter pieces from the inside keeps them up to the sides of the cylinder and also to the inclined ends of the piece v . The cross-bar h^2 is guided by staples k^2 , and as it turns with the piston-wheel and just when it arrives under the aperture through which the abutment works it catches under two lugs l^2 , that are firmly secured to the cylinder-heads. These lugs retain the piston and prevent it catching in the aperture of the abutment, and as soon as the piston has passed said aperture the cross-bar h^2 is released and the packing-piece v is forced out again against the inner surface of the cylinder by the springs j^2 .

The correct position of the piston-wheel is ascertained by a pointer L, which is secured to the frame or bed-plate of the engine and which stands right opposite to a mark or groove m^2 in the central shaft C. If the piston-wheel works loose, this pointer shows at once which side wants screwing up, and by means of the screws t the piston-wheel can always be brought in a correct position. The central shaft C of the piston-wheel has its bearings in pillow-blocks M, and the journals of the shaft are made tapering and they run in conical boxes N, that are secured to the pillow-blocks by means of screws n^2 . If the boxes N wear out on the under side, it is only necessary to tighten up the screws n^2 in order to bring the piston-wheel back to its correct position in a vertical direction. Thus it will be seen that with my engine the piston-wheel can be adjusted at all times by means of the screws t and n^2 , all of which can easily be reached from the outside, it being hardly necessary to stop the engine for the purpose of accomplishing this object, and at the same time the joints are rendered perfectly tight and any wear of the packing in any part of the engine is either compensated by the action of the springs acting thereon or by the screws t on the outside of the cylinder-heads.

Having thus fully described my invention, what I claim as new, and desire to secure by Letters Patent, is—

1. The arrangement of the dogs G G', with square notches $k k'$, in combination with the

tooth i , bell-crank levers $l m l' m'$, arms $o' o'$, toothed segments $h h'$, and abutment E, all constructed and operating as and for the purpose set forth.

2. The arrangement of the cam H and cut-off valve I, in combination with the rising and falling abutment E, as and for the purpose described.

3. The employment of the conical packing-rings q and inclined faces r on the piston-wheel A, in combination with the conical projections s on the inner sides of the disks J, constructed and operating in the manner and for the purpose specified.

4. The arrangement of the angular packing-pieces b^2 , hinged pins e^2 , and springs f^2 , in combination with the rectangular packing-pieces a^2 , pins d^2 , and springs c^2 on the sides of the abutment E, as and for the purpose described.

5. The arrangement of the locking spring-bar h^2 and lugs t^2 , in combination with the self-adjusting spring-piston D, constructed and operating in the manner and for the purpose specified.

6. The employment of the stationary pointer L, in combination with groove or mark m^2 on the rotary central shaft C, as and for the purpose set forth.

7. The arrangement of the conical journal-boxes N, in combination with the tapering journals of the rotary shaft C, constructed and operating as and for the purpose described.

CHRISTEN CHRISTENSEN.
